[57] **CLAIM**

The ornamental design for a comfort pillow, as shown and described.

DESCRIPTION

FIG. 1 is a front perspective view taken from the right end of a comfort pillow showing my new design;

FIG. 2 is a top plan view thereof;

FIG. 3 is a front elevation view thereof, the rear elevation view being a mirror image of the front elevation view shown;

FIG. 4 is a right end elevation view thereof, the left end elevation view being a mirror image of the right end elevation view; and,

FIG. 5 is a bottom plan view thereof.
